SHAKER CONVEYER

Tage Georg Nyborg, Worcester, England, assignor
of one-half to The Mining Engineering Com-
pany Limited, Worcester, England

Application March 24, 1937, Serial No. 132,838
In Great Britain June 10, 1936

9 Claims. (Cl. 198—220)

This invention relates to shaker conveyers and has for an object to provide improved means for loading or discharging such conveyers.

Various arrangements of telescopic shaker loaders have hitherto been in use. In general the application is the advancing of a wide mouthed or shovel trough at the end of the shaker trough line into the pile of loose material (for example coal) by disconnecting the shovel trough from the main trough line on the forward or conveying stroke and clamping it strongly to the trough line on backward or return stroke for the necessary number of strokes to give the required advance. Under certain conditions the advance of the shovel trough may be sufficiently powerful to pick up the loose material without assistance, or, under other conditions some manual feeding in of the material may be required.

A form of clamp now in general use comprises clamping blocks bearing on the upper strengthened flanges of the shovel trough the clamping action being dependent on springs and the un-clamping being performed by manual operation of a lever and cam. This design possesses the disadvantage that the telescopic loader is dependent for its operation on the correct synchronisation of the manually operated lever, and as this is reciprocating with the trough line, correct operation is extremely difficult and there is so much lost motion that it has not been found practicable to operate telescopic shaker loaders on steep gradients. The manual effort required to operate the lever is considerable and one or two men are required permanently at this point.

An object of the present invention is to provide, in a shaker conveyer having two sections in telescopic relation to one another, improved means for advancing and retracting one of these sections relatively to the other.

A further object of the invention is to provide means for advancing or retracting a section of a shaker conveyer relatively to an adjacent section which continues to operate automatically on the desired shaker stroke.

Yet another object of the invention is to provide means for advancing or retracting a section of a shaker conveyer relatively to an adjacent section which is controllable, for example manually, from a remote point.

It will be realised that the mechanism is not only appropriate to a loader when used at the loading end, but also to a delivery section when used at the delivery end, for example, of a stowing conveyer.

In the preferred forms of the invention one or more clamps are rendered operative in each direction by the presence of a movable wedge or abutment which is under load during the movement in that direction, so that the clamp or clamps can be rendered inoperative in either di-

rection by removal of the appropriate wedge or abutment while it is not under load.

Various other objects and advantages will be apparent from the following descriptions of embodiments of the invention and the novel features will be particularly pointed out in connection with the appended claims.

In the accompanying drawings:

Fig. 1 is a side view of part of a conveyer in accordance with the invention,

Fig. 2 is a sectional plan view taken on the line II—II of Fig. 1,

Figure 3 is a cross-section taken on the line III—III of Figure 2, and

Figure 4 is a plan view of a modification.

In the form shown at Figures 1 to 3, the trough section 1 is connected to a shovel (not shown) and will hereinafter be termed the "shovel trough". The trough section 2 is connected to the main run of the conveyer and is reciprocated longitudinally in the usual manner, material loaded onto the conveyer being caused to flow in the direction of the arrow A.

The shovel trough 1 can move longitudinally so as to telescope with the trough section 2, hereinafter termed the telescopic trough. Both the shovel trough 1 and the telescopic trough 2 have longitudinal bars 3, 3' welded into curled flanges 4, 4' at their upper edges and the alignment of the two troughs 1 and 2 is maintained by means of two or more top flanged guide rollers 5, and two or more vertical side rollers 6 mounted on a supporting frame 7 for the loader and by rollers 8 carried by the telescopic trough 2 engaging with a longitudinal bar 9, welded to the middle of the underside of the shovel trough 1.

These clamping shoes 10, 10' are connected by a link 11 in such a manner that if the angularity of the link is increased or tends to increase, as for example by holding one of the shoes stationary and applying pressure to the other shoe in a direction parallel to the longitudinal bar 9, the shoes 10, 10' clamp the bar 9.

Pressure in the longitudinal direction is applied to the shoes 10, 10' to clamp them to the bar 9 by abutment members fixed to the telescopic trough 2. One abutment comprises a removable wedge 12 loaded by a spring loaded piston 13 and is arranged to come into contact with the shoe 10 on the backward stroke of the conveyer. Another abutment comprises a removable wedge 14 positioned by an adjustable set screw 15 and arranged to come into contact with the other shoe 10' on the forward stroke of the conveyer. A further abutment comprising an adjustable set screw 16 is arranged adjacent the shoe 10 at the end remote from the wedge 12 and an abutment comprising an adjustable set screw 17 is arranged adjacent the end of the shoe 10' remote from the wedge 14. The adjustment of these set

screws 16 and 17 is such that they are just out of contact with the shoes 10, 10' when the wedge abutments 12, 14 are in operative position.

Means are provided to allow of the withdrawal 5 of the wedge abutment 12, by an operator. Such means comprise a flat plate 18 pivoted at 19 to the telescopic trough and connected to the wedge 12 by a link 20. A spring pressed piston 21 presses against the plate 18 so as to maintain the 10 wedge 12 in the operative position. A rope or the like 22 is connected to the plate 18 by means of a shackle 23 and is led away to a position easily accessible to the man responsible for the shovel loading. Similar means are provided for 15 withdrawing the wedge 14.

When it is desired to have the shovel trough 1 rigidly clamped to the telescopic trough 2 and moving with it on both forward and return strokes of the conveyer, both wedge abutments 12 and 14 20 are in position. When the trough line begins its return stroke, the wedge abutment 12 strikes the shoe 10 and moves it over slightly to clamp the bar 9 and thus move the shovel trough 1 in the same direction as the conveyer. At the start 25 of the forward or conveying stroke, the other wedge abutment 14 strikes the other shoe 10' and moves it over to lock the shoes 10, 10' on to the bar 9 and thus move the shovel trough 1 in the forward direction of the conveyer stroke. It 30 will be appreciated that the movement to clamp or unclamp is very small and thus the lost motion between the shovel and telescopic troughs is small.

When it is desired to advance the shovel trough 35 1, as for example into a heap of coal, the wedge abutment 14 which would otherwise come into contact with the shoe 10' on the forward stroke of the conveyer, is withdrawn by means of the associated lever plate 18 and rope 22 and the 40 clamp then operates on the return stroke of the conveyer but is free on the conveying stroke.

When it is desired to retract the shovel trough 1, the wedge abutment 12 which would otherwise come into contact with the shoe 10 on the return 45 stroke of the conveyer is withdrawn and the clamp then operates on the conveying stroke but is free on the return stroke.

The appropriate wedge is, in each case, withdrawn during the period when it is not under 50 load, that is the wedge 12 during the conveying stroke and the wedge 14 during the return stroke.

The abutment 13 operating the shoe 10 on the return stroke of the conveyer is loaded by means 55 of spring piston 24 so that if the shovel strikes some large or solid object damage to the troughing is avoided. When the resistance to forward motion of the shovel exceeds the spring load, the abutment 13 moves backwards and the set screw abutment 17 strikes the shoe 10' and releases the clamp.

The wedge abutment 15 is made adjustable by means of a set screw 25 to allow for wear of the shoes 10 and 10'.

65 A modified form of the clamping means is shown in Fig. 4. The shoes 10, 10' grip the bar 9 when the link member 11 is displaced angularly. Pressure to displace the link 11 is applied directly to the ends of the link 11 from the abutments 70 13 or 15 through the wedge abutments 12 or 14 and through members 30 or 31 respectively. These members 30 and 31 are slidable in grooves formed in the shoes 10 and 10', and have the faces which engage the wedges tapered to the 75 same inclination as the wedges. Similarly the

abutments 16 and 17 engage the ends of the link 11 through members 32 and 33 also slidable in the shoes 10 and 10'.

The spring pressed piston 21 bearing on the plate 18 may be in this form arranged parallel to 5 the line of the conveyer instead of at right angles thereto as shown in Fig. 2.

The length of the telescopic trough 2 is preferably such that the difference in advance between the inner and outer positions of the shovel is 10 more than the length of a standard trough, so that the shovel trough 1 can be extended to its full extent and the telescopic clamp moved up leaving sufficient space for the insertion of a 15 standard trough.

It will be understood that the invention is not restricted to the details of the preferred forms described above but that it includes such modifications as come within the broad idea underlying the invention. 20

I claim:

1. In a shaker conveyer comprising two sections in telescopic relation to one another, means for advancing or retracting one of these sections relatively to the other comprising a longitudinal bar rigidly connected to one of these sections, shoes arranged on each side of the longitudinal bar, an inclined member embracing the shoes, fixed abutments carried by the other section, removable abutment members between the fixed 30 abutments and the inclined member pressing eccentrically upon the inclined member during movement of the conveyer so as to vary its angularity and move the shoes to clamp the bar and means for selectively rendering the removable 35 abutment members inoperative during the forward and backward stroke of the conveyer respectively.

2. In a shaker conveyer comprising two sections in telescopic relation to one another, means for advancing or retracting one of these sections relatively to the other comprising a longitudinal bar rigidly connected to one of these sections, shoes arranged on each side of the longitudinal bar, an inclined member embracing the shoes, 45 fixed abutments carried by the other section, removable abutment members between the fixed abutments and the shoes pressing upon the shoes during movement of the conveyer so as to vary the angularity of the inclined member and move 50 the shoes to clamp the bar and means for selectively rendering the removable abutment members inoperative during the forward and the backward stroke of the conveyer respectively.

3. In a shaker conveyer comprising two sections in telescopic relation to one another, means for advancing or retracting one of these sections relatively to the other comprising a longitudinal bar rigidly connected to one of these sections, a pair of shoes arranged one on each 60 side of this bar, an inclined member embracing these shoes, fixed abutments carried by the other section and arranged one at each end of each shoe, a removable abutment member between one of said shoes and one of said fixed abutments, a second removable abutment member between the other of said shoes and the fixed abutment at the end of this shoe remote from the first mentioned removable abutment member, said first mentioned removable abutment member 70 transferring pressure from the corresponding fixed abutment to the shoe to increase the angularity of the inclined member and cause the shoes to grip the longitudinal bar during the forward stroke of the conveyer, said second member 75 trans-

- tioned removable abutment member transferring pressure from the corresponding fixed abutment to the shoe to increase the angularity of the inclined member and cause the shoes to grip the longitudinal bar during the backward stroke of the conveyer, and means for selectively removing the removable abutment members to render the clamping means inoperative during the corresponding stroke of the conveyer.

4. In a shaker conveyer comprising two sections in telescopic relation to one another, means for advancing or retracting one of these sections relatively to the other comprising a longitudinal bar rigidly connected to one of these sections, a pair of shoes arranged one on each side of this bar, an inclined member embracing these shoes, fixed abutments carried by the other of these sections and arranged one at each end of each shoe, a removable abutment member between one of said shoes and one of said fixed abutments, a second removable abutment member between the other of said shoes and the fixed abutment at the end of this shoe remote from the first mentioned removable abutment member, said second-mentioned fixed abutment member being spring-loaded and arranged to move in the forward direction of the conveyer under abnormal load, said first mentioned removable abutment member transferring pressure from the corresponding fixed abutment to the shoe to increase the angularity of the inclined member and cause the shoes to grip the longitudinal bar during the forward stroke of the conveyer, said second mentioned removable abutment member transferring pressure from the corresponding fixed abutment to the shoe to increase the angularity of the inclined member and cause the shoes to grip the longitudinal bar during the backward stroke of the conveyer and means for selectively removing the removable abutment members to render the clamping means inoperative during the corresponding stroke of the conveyer.

5. In a shaker conveyer comprising two sections in telescopic relation to one another, means for advancing or retracting one of these sections relatively to the other comprising a longitudinal bar rigidly connected to one of these sections, a pair of shoes arranged one on each side of this bar, an inclined member embracing these shoes, fixed abutments carried by the other of these sections and arranged one at each end of each shoe, a removable abutment member between one of said shoes and one of said fixed abutments, a second removable abutment member between the other of said shoes and the fixed abutment at the end of this shoe remote from the first mentioned removable abutment member, said second-mentioned fixed abutment member being spring-loaded so as to relieve excessive load, removable abutment members which on slight or incipient relative motion between the sections transfer a load from the fixed abutment means to the inclined member so as to increase its angularity and move the shoes to clamp the longitudinal bar and means for selectively withdrawing the removable abutment members to render the clamping means inoperative during selected movement of the conveyer in either direction.

6. In a shaker conveyer comprising two sections in telescopic relation to one another, means for advancing or retracting one of these sections relatively to the other comprising an inclined member, abutment means automatically operative by slight or incipient relative motion between the sections to apply a load eccentrically to this inclined member so as to increase its angularity and cause it to clamp the elements together and means for rendering the abutment means inoperative during selected movement of the conveyer in either direction.

7. In a shaker conveyer comprising two sections in telescopic relation to one another, means for advancing or retracting one of these sections relatively to the other comprising clamping means comprising a longitudinal bar rigidly connected to one of these sections, shoes arranged on each side of the longitudinal bar, an inclined member embracing the shoes, fixed abutment means carried by the other of these sections, removable abutment members which on slight or incipient relative motion between the sections transfer a load from the fixed abutment means to the inclined member so as to increase its angularity and move the shoes to clamp the longitudinal bar and means for selectively withdrawing the removable abutment members to render the clamping means inoperative during selected movement of the conveyer in either direction.

8. In a shaker conveyer comprising two sections in telescopic relation to one another, means for advancing or retracting one of these sections relatively to the other comprising clamping means comprising a longitudinal bar rigidly connected to one of these sections, shoes arranged on each side of the longitudinal bar, an inclined member embracing the shoes, fixed abutment means carried by the other of these sections, one of these fixed abutment means being spring loaded so as to relieve excessive load, removable abutment members which on slight or incipient relative motion between the sections transfer a load from the fixed abutment means to the inclined member so as to increase its angularity and move the shoes to clamp the longitudinal bar and means for selectively withdrawing the removable abutment members to render the clamping means inoperative during selected movement of the conveyer in either direction.

9. In a shaker conveyer comprising two sections in telescopic relation to one another, means for advancing or retracting one of these sections relative to the other comprising an inclined member, abutment means automatically operative by slight or incipient relative motion between the sections to apply a load eccentrically to said inclined member to vary its angularity, means limiting the possible angularity of the inclined member and utilizing a component of the load applied by the abutment means to prevent effective relative movement between the sections by clamping action, and means for rendering the abutment means inoperative during selected movement of the conveyer in either direction.

TAGE GEORG NYBORG.
